UNITED STATES PATENT OFFICE

HENRY C. KIRK, OF BALTIMORE, MARYLAND; COLONIAL TRUST COMPANY EXECUTORS
OF SAID HENRY C. KIRK, DECEASED

OIL TREATMENT PROCESS AND APPARATUS THEREFOR

Application filed December 8, 1927. Serial No. 238,648.

This invention relates to processes of treatment of oils, and particularly hydrocarbon oils, and apparatus therefor.

In the prior art methods of heat treating oils for the recovery of gasoline and other products therefrom, considerable difficulty has been experienced in operating such processes due to the formation of carbon. Shutdowns are frequently required due to the accumulation of this carbon in the system or apparatus, necessitating its removal before operation can be begun again. Such shutdowns not only are uneconomical due to the discontinuity of the process, but there is a tremendous element of expense in labor involved in the removal of the accumulated carbon, which is hard and graphitic or coke-like. The suggestions in the prior art for elimination of "carbon" trouble are legion, but heretofore no successful solution of the problem has been found.

One of the primary objects of this invention is the carrying out of the oxygenation heat treatment of oils and related substances wherein no hard, coke-like carbon is formed or deposited, any carbon which is formed during the process being soft or mud-like and readily removable with the tar drawn off in the tar line.

Many other objects and advantages will appear from the more detailed description set forth below, it being understood however that this more detailed description is given by way of illustration, and not as limiting, since various changes may be made in the method and apparatus by those skilled in the art, without departing from the spirit and scope of this invention.

In connection with this more detailed illustrative description, consideration should be taken of the accompanying drawings wherein there is shown, in

Figure 1, an elevation partly in section of a treatment still embodying the invention; in

Figure 2, a detail partly in section of the air and oil inlet nozzles; and in

Figure 3, a detail partly in section of one of the ends of the air-oil inlet nozzles.

Figure 4, an elevation partly in section of a treatment still embodying the invention

and showing the use of recovered oil in the circulation system; and in

Figure 5, an elevation partly in section of a treatment still embodying the invention showing the use of recovered oil from the tank in the circulation system.

The invention is well illustrated in a process of treating petroleum oils under substantial pressure and at relatively elevated temperatures with air or other oxygen containing gas, wherein vaporous and gaseous products, and a liquid tar residuum are withdrawn from the treatment zone.

In carrying out such a process, in order to prevent formation or deposition of hard, coke-like carbon, a positive, controlled, uniform circulation of the oil undergoing treatment is maintained at all times within the body of the oil itself. To this end, the still 1 is partly filled with oil to a convenient level 2.

This oil may be preheated either before entering the still or after it is placed therein by any suitable heating means (not illustrated). Air is forced into the oil through air inlet pipe 3 desirably provided with a series of nozzles 4. In the construction illustrated, the air inlet nozzles are mounted on a ring 5, the latter being connected to air inlet pipe 3 by connecting pipes 6, 6 and 7. Surrounding each air nozzle is a concentric tube 8 through which oil passes, the tubes 8 being mounted on a ring 9 to which ring, oil is fed through inlet pipe 10'. Near the upper oil level, but submerged in the oil is an oil inlet ring 10 connected by pipe 11 to a source of oil supply. This upper oil ring is desirably supplied on its under side 12 with a series of openings through which oil may be projected

preferably under pressure into the body of oil in the still 1. The bottom of the still is desirably conical in shape, and near the bottom thereof below the air-oil inlet nozzles, a lower oil inlet pipe 13 is placed desirably provided with a series of openings 14 along its side wall, whereby oil may be projected into the body of oil in the still, but below the air inlet nozzles. The pipe 13 is fed with oil by pipe 15 connected with a source of oil supply.

In the structure illustrated, a common source of oil supply 16, feeds oil to the

inlet pipes 10', 11 and 15 through control valves 17, 18, 19; the pipes 10', 11 and 15 carrying pressure gages, 20, 21, 22. A vapor outlet 23 is conventionally illustrated, which 5 may be sufficiently large for giving access to the interior of the still. Tar or residuum or oil is withdrawn through the tar line 24, located in the bottom of the still 1. Vapors and gases may be withdrawn from the upper 10 part of the still in the usual manner.

In operation, the still is filled with oil to the desired level. Temperature and pressure conditions having been adjusted for the purposes in hand, air is forced into the oil 15 through air inlet 3 and oil is injected through oil inlets 10', 11 and 14. The oil entering through the tubes or nozzles 8 together with the air entering through nozzles 4 set up an inner zone of rising liquid and gas within 20 the central portion of the column of oil. Each air current is thus enveloped in an enclosing sheath of oil. The oil forced through upper ring 10 produces an outer zone of downwardly moving oil. When gas or vapor 25 reaches the upper portion of the oil, it escapes to the vapor space above the oil, while the oil carried to the upper level is returned with the outer downwardly moving oil. Positive circulation is thus set up in the body of oil, 30 the velocity of circulation being controlled by the rate of feed of air and oil, to the inlet pipes and/or nozzles. Since certain heavier materials tend to segregate in the lower portion of the still, at a point below the air inlet nozzles, these heavier materials are kept 35 in circulation by the oil entering from pipe 13. It is thus seen that circulation of the oil within the body of oil itself, is maintained at all times so that no portion of the oil undergoing treatment is allowed to come to rest 40 at any time within the still proper. Furthermore, the rate of circulation is substantially uniform throughout the body of oil.

Since the formation of hard, adherent, coke-like carbon in any substantial amount appears to take place only when the heated oil is allowed to come to rest on a heated surface or in contact with a heated substance, the continuous forced, uniform circulation maintained 45 throughout the body of oil, substantially eliminates the formation of such carbon.

The oil used for producing circulation may be obtained from any desirable sources, 50 and need not be untreated stock alone. In fact, questions of economy require the use of backtrap or returned oil such as oil or condensates from the bubble towers, lighter portions from the tar tank, etc., as subsidiary 55 sources of oil to be mixed with the new or untreated oil.

The following example illustrates a specific application of the invention. The stock treated was fresh paraffin base gas oil. The 60 charging pump was started and oil charged

from the supply tank through the preheater. As soon as the latter was full of oil, the preheater fires were lighted. When the desired oil level in the still was reached, charging was discontinued, and the oil circulated from the still back to the preheater with a surge pump until the temperature of the oil in the still reached 550° F. When the oil temperature in the still reached 525-550° F., air was cut into the still, circulation continued 70 and charging of the small amount of fresh charge oil from the oil tank was resumed. When the pressure in the still reached 100 lbs./sq. in., equalizing with the bubble tower was started. As soon as the bottom of the bubble tower reached 450° F. and enough condensate was available in the base of the tower the aforesaid circulation was discontinued, and the backtrap was returned 75 through the preheater, this return of the backtrap through the preheater being continued throughout the remainder of the run. The charging oil and backtrap passing to the still were proportioned between the top and bottom oil inlets and the combination air-oil jets. Proper operating conditions were now maintained. The pressure in the still and bubble tower was 350 lbs./sq. in., the temperature in the still top being approximately 710° F. The air was forced into the still under an average pressure of 443 80 lbs./sq. in. The oil charged was about 179 bbls. per hour, and air charged was about 835 cu. ft. per minute or 2795 cu. ft. per bbl. of oil charged. There was obtained about 85 5.7 bbls. of distillate per hr. The run was continued for about two hundred hours and then arbitrarily discontinued. Inspection of the still and still contents showed that there 90 had been no formation of hard, adherent or coke-like carbon.

The above given description of the apparatus and its operation, and the specific example, should not be taken as limiting. In the illustrated form of the device, but one upper oil inlet ring and but one lower oil inlet pipe is shown. However as many such inlets may be used as are desired, although one of each is generally sufficient to produce the required degree of circulation, in conjunction with the duplex oil-air jets. While these oil-air jets have been shown as concentric tubes or nozzles, separate oil and air nozzles may be used. The duplex nozzle illustrated has however given excellent results in practice.

Further the arrangement of upwardly directed oil-air nozzles at a centralized portion of the column of oil, with a corresponding downwardly directed spray ring has proved satisfactory in actual tests, since the gases and vapors formed in the oil are confined to an inner, rising column of oil, from which they readily escape to the vapor space without the generation of wild gas or vapor bubbles.

bles that would seriously interfere with the circulatory currents set up in the body of oil. This factor is an important one, completely overlooked in the prior art. Besides 5 confining the gas and vapor bubbles to the inner rising column of oil where they assist in enhancing the circulation, the devices described above set up a pronounced circulation in the body of oil, upwardly in the central 10 portion thereof, outwardly at the upper level, and downwardly along the shell and outer portion of the body of oil, and then inwardly again at a zone approximately on a line with the oil-air jets.

15 This circulatory movement is the preferred one in processes involving heat treatment with concurrent oxygenation and disintegration. However if desired, other arrangements of apparatus with consequent 20 variation in the circulatory movements, may be made, it being essential only that in any such arrangement, that sufficient circulation be obtained for the ends sought.

25 While the apparatus has been diagrammatically illustrated as applied to a vertical still, it may by suitable adjustment be used with a horizontally disposed still. In this case, the oil-air jets may form a series of nozzles projecting from a pipe along the 30 bottom of the still, while the upper oil spray inlet may be disposed as two horizontally placed pipes with downwardly directed spray openings, submerged in the upper portion of the body of oil but parallel with the 35 pipe supplying the oil-air jets. Any tar collecting below the oil-air jets may be flushed along the bottom of the still to one end thereof where it may be removed.

40 It is desirable to carefully consider the ratio of the incoming fluids and the force exerted by them, in relation to the volume of liquid to be circulated. To obtain the required circulation, either larger volumes of liquid may be circulated, or the differential 45 of pressure may be increased. For example, a greater volume of oil may be circulated through the still than is actually undergoing treatment therein due to the fact that vapors and gases, and tar are removed either continuously or intermittently. Or the incoming oil may be injected under pressures sufficient to produce the circulatory movement desired in the body of oil itself. However, 50 in any case, for the best results, the oil level 55 in the still desirably should remain substantially constant. Not only may the several sources of oil for causing circulation, described above, be used, but the backtrap, light tar, fresh stock, etc., may be proportioned 60 between the various oil inlets, as desired. When using oil from the light tar tank, more frequent drags through the tar line, may be made.

65 The oil fed in may be readily used to control or regulate the temperature in the still,

since the incoming oil is cooler than that in the still. If the temperature in the upper portion of the body of oil undergoing treatment is too high, more of the incoming oil may be charged at that point. The use of oil inlet sprays at several points in the still 10 will enable this regulation of temperature therein to be readily maintained.

The use of cooled oil for keeping the temperature down, particularly when air at increased temperatures is used, is considered to be more advantageous than is the use of internal cooling agents such as steam, when used with the incoming air. The latter expedient may however be employed when desired. The differential on the oil charge line 75 need be sufficient only to produce the desired degree of circulation.

80 For the most efficient circulation, the vertically disposed sprays have proved best. However, the spray openings and nozzles may be angularly disposed if desired to give a tangential or whirling movement within the circulating body of oil, without destroying 85 the circulatory current. Since in such cases much of the force of the injected fluids is consumed in producing such whirling movement thereby diminishing the force available for producing the circulation proper, the vertically disposed sprays and 90 nozzles are considered to be preferable.

95 It should be particularly noted that in the present case, all stirrers are eliminated, and in fact no elements in motion are required. Further the still is kept practically free from 100 apparatus, the rings and pipes placed therein in accordance with the present invention being reduced to a minimum, and of such simple construction that with the elimination of hard carbon formation, no attention is 105 required by those pipes, etc. within the still. The stuffing boxes hitherto required in the prior art are avoided with resultant elimination of leaks through such elements—a major 110 source of trouble in prior art devices.

115 The present invention maintains the oil or other liquid in circulation, permitting no quiescent zones therein, and no dissemination of wild gas or vapor bubbles throughout the liquid. The circulation is maintained substantially uniform throughout the oil undergoing treatment by supplementing the movement caused by the oil-air jets, at various points in the body of oil removed from the oil-air jets, the secondary circulatory movements complementing that initially induced at the oil-air jets. Sufficient sprays, etc. should be used to obtain the required circulation, and for any given still may be readily determined in accordance with the present 120 disclosure.

125 The present invention is not limited to application to the specific example hereinabove set forth. Such circulation may be utilized in any process of treatment of liquid 130

or molten materials wherein uniformity of operating conditions are required. In the treatment of hydrocarbon oils, by the present method, the fluids used for producing circulation are air and oil. But while these are essentially desirable in the indicated process, any fluids may be used depending on material undergoing treatment and the process involved. Even in the indicated process, 10 steam, preferably superheated may be used at some jets, and residual gases such as those obtained from petroleum stills, in general, or in the process itself, may be utilized as part of the injected fluid.

15 The present invention is particularly important in the air blowing of hydrocarbon oils or related materials, particularly under pressure, in view of the fact that hard carbon formation is substantially avoided. Among 20 the materials that may be treated there may be mentioned petroleum and its various distillates, shale products and tars, pitches, waxes, paraffin, sludges, residues from the petroleum industry, asphaltic oils, malthas, 25 asphalt, cracked oils and residues from cracking stills, wood tar oils and wood tars, peat distillates, lignite distillates, distillation products from coal, and oils such as petroleum oil containing solid substances in suspension, such as coal, coke, peat, carbon, etc.

30 While air is primarily used as the oxygen containing gas, oxygen, oxygen-nitrogen mixtures, etc. may be utilized.

35 The invention is particularly useful in heat treatment processes for petroleum, carried out under superatmospheric pressure, but may be utilized as well when the treatment is either at or below atmospheric pressures. Substantial pressures of from 50 to 40 500 lbs./sq. in. with temperatures ranging from 300 to 1000° F. are usable in treating petroleum or other hydrocarbon oils.

45 Solid bodies or activating substances may be present but these are not essential, and are generally avoided.

50 The still should be of heavy plate sufficient to withstand the pressures that may be developed.

55 The level of oil undergoing treatment is desirably maintained constant, and the air injected should be substantially deoxygenated during its travel through such column of oil. Deoxygenation depends on a number of factors including the nature of the material undergoing treatment, the depth of such material, the temperature and pressure conditions.

60 The products of the process includes fixed gases containing hydrocarbons, condensates both water soluble and water insoluble, from which a wealth of desirable hydrocarbons, oxygen-containing compounds, resins, gums, gasoline substitutes of anti-knocking characteristics, solvents, etc., etc. may be recovered, and tars or residuum such as still bot-

70 toms convertible into, or useful for recovery therefrom, of, valuable derivatives.

75 In referring above to the oil which may be used for circulation purposes, oil from the light tar tank and other sources has been referred to. In addition the light tar itself is preferable, it being generally undesirable to use the heavier tar portions. Further more oil may be withdrawn from the still itself, at any particular point desired and recharged thereto through any of the injecting devices described in order to enhance the circulation. If the drags through the tar line are taken at very frequent intervals or at least at a rate greater than the accumulation of tar or heavier materials in the bottom of the still, oil may be withdrawn at this point and this oil used for causing circulation in any of the manners described above.

80 Thus in the diagrammatic showing of Figure 4, the vapors and gases are taken off from the still 1' and carried to the bubble tower 2'. In the bubble tower, part of the vapors are condensed to form recovered oil and related products, which may then be sent back and utilized in the charge oil inlet for producing the circulation in the still.

85 In Figure 5, the diagrammatic showing includes the utilization of oil recovered from the tar tank. For this purpose the material taken off in the tar line 20' proceeds to the tar tank 21', where the oil preferably the lighter oil is allowed to separate, and is recovered and returned to the circulating system through the charge oil inlet.

90 A remarkable feature of the present invention is the substantial absence of hard or adherent carbon not only from the oil in the still, but also from the tar or residuum withdrawn therefrom. This fact strikingly 95 differentiates the present invention over prior art practice.

100 Having thus set forth my invention, I claim:

110 1. A process of heat treating hydrocarbon oils to produce lighter distillates therefrom which comprises maintaining a body of oil under conversion conditions of temperature and pressure, and injecting air and oppositely directed non-planar oil streams thereinto at a sufficient number of points to produce substantially uniform circulation throughout the body of oil, of such rate as to substantially eliminate the formation of hard or adherent carbon.

115 2. A process of heat treating hydrocarbon oils to produce lighter distillates therefrom which comprises injecting air and oppositely directed non-planar oil streams within a body of oil under conversion conditions of temperature and pressure, to produce circulation within the body of oil of character and velocity sufficient to prevent formation of hard carbon.

3. In a process as set forth in claim 2, the steps of obtaining a liquid product from the oil undergoing treatment and injecting that liquid product into the maintained body of oil as a circulation producing stream.

4. In a process of heat treating a body of petroleum to produce lighter distillates therefrom maintained under conversion conditions of temperature and pressure with air injected thereinto, the step of injecting oppositely directed non-planar oil streams within the body of petroleum to produce circulation therein sufficient to eliminate the formation of hard carbon.

5. Apparatus for heat treating oils to produce lighter distillates therefrom which comprises a still for maintaining a body of oil at conversion temperatures and pressures, and means for injecting air and oppositely directed non-planar oil streams within said body of oil to produce circulation therein of character and velocity sufficient to prevent formation of hard carbon.

6. In apparatus as set forth in claim 5, means for obtaining a liquid product from the oil undergoing treatment and means for injecting that liquid product into the maintained body of oil as a circulation producing stream.

7. Apparatus for heat treating oils to produce lighter distillates therefrom which comprises a still for maintaining a body of oil under conversion conditions of temperature and pressure, air and oil inlets near the bottom of said still, for injecting upwardly directed streams of oil and air, an oil inlet in the upper part of the still but below the oil level for injecting circumferentially and downwardly directed streams of oil, means for receiving tar which settles below the air inlets, means for maintaining said tar in circulation below said air inlets, an outlet conduit for vapors and gases in the upper portion of said still, and means for removing tar from the tar receiving chamber.

8. A process of heat-treating hydrocarbon oils to produce lighter distillates therefrom which comprises maintaining a body of oil under conversion conditions of temperature and pressure, injecting streams of air and oil within said body of oil to produce movement of a substantial portion of said body of oil in a given direction, and injecting a second stream of oil into said body of oil at a point removed from the point of injection of the aforesaid air and oil streams whereby the aforesaid movement of the portion of the body of oil is enhanced, and the deposition of hard carbon is substantially eliminated.

9. A process of heat-treating hydrocarbon oils to produce lighter distillates therefrom which comprises maintaining a body of oil under conversion conditions of temperature and pressure, injecting streams of air and oil within said body of oil to produce con-

trolled movement of a portion of the body of oil for a given distance, and injecting a second stream of oil within said body of oil at the point where such controlled movement of the portion of the body of oil would normally tend to cease, whereby controlled movement of the oil is maintained and the deposition of hard carbon is substantially eliminated.

10. A process of heat treating hydrocarbon oils to produce lighter distillates therefrom which comprises maintaining a body of oil under conversion conditions of temperature and pressure, injecting upwardly directed streams of air within the body of oil in a lower zone thereof, to produce an upwardly moving current of oil and gas and injecting a downwardly directed oil stream into the body of oil in an upper zone thereof to produce a downwardly moving oil current in said body of oil, whereby circulatory currents are set up throughout the body of oil and the deposition of hard carbon is substantially eliminated, allowing residuum to settle below the air inlets but circulating said residuum below said air inlets by injected oil currents.

11. A process of heat treating hydrocarbon oils to produce lighter distillates therefrom which comprises maintaining a body of oil under conversion conditions of temperature and pressure, injecting upwardly directed streams of air within the body of oil in a lower zone thereof, the incoming air streams being entirely enveloped within injected oil streams, said injected streams of air producing an upwardly moving current of oil and gas, and injecting a downwardly directed oil stream into the body of oil in an upper zone thereof to produce a downwardly moving oil current in said body of oil, whereby circulatory currents are set up throughout the body of oil and the deposition of hard carbon is substantially eliminated.

12. In a process of heat treating oil under conversion conditions of temperature and pressure with air streams injected thereinto to produce lighter distillates therefrom, the step of entirely enveloping such air streams within streams of injected oil.

13. Apparatus for heat treating hydrocarbon oils to produce lighter distillates therefrom which comprises a still for maintaining a body of oil under conversion conditions of temperature and pressure, means for injecting air in upwardly directed streams, into the body of oil near the bottom thereof, means for injecting oil in upwardly directed streams along with the air, and means for injecting downwardly directed oil streams into the body of oil near the upper level thereof, supplementing the upwardly directed streams, whereby circulatory currents are set up in the body of oil.
